United States Patent Office

Des. 184,198
Patented Dec. 30, 1958

184,198

EXHAUST EXTENSION GRILLE

Linus E. Russell, Springfield, Ohio, assignor to Peters & Russell, Inc., Springfield, Ohio, a corporation of Ohio

Application October 31, 1956, Serial No. 43,612

Term of patent 14 years

(Cl. D14—6)

Fig. 1 is a perspective view of an exhaust extension grille embodying my design;

Fig. 2 is a top plan view thereof; and

Fig. 3 is an end view thereof.

The dotted line representation is used merely for illustrative purposes.

I claim:

The ornamental design for an exhaust extension grille, substantially as shown and described.
